UNITED STATES PATENT OFFICE.

SUMMERS BROWN, OF NEW YORK, N. Y.

PAPER-FEEDING DEVICE FOR PRINTING-MACHINES.

No. 892,358.

Specification of Letters Patent. Patented June 30, 1908.

Original application filed July 9, 1906, Serial No. 325,343. Divided and this application filed April 11, 1907.
Serial No. 367,681.

To all whom it may concern:

Be it known that I, SUMMERS BROWN, a subject of the King of Great Britain, residing at New York, in the county of New York and 5 State of New York, have invented certain new and useful Improvements in Paper-Feeding Devices for Printing-Machines; and I do hereby declare the following to be a full, clear, and exact description of the invention, 10 such as will enable others skilled in the art to which it appertains to make and use the same.

This invention relates to paper-feeding mechanism for cylinder printing machines 15 and consists in the construction and combination of parts hereinafter more particularly set forth and claimed.

In the accompanying drawings Figure 1 represents a side elevation of a machine embodying my invention; Fig. 2 represents a 20 plan view of the same; and Fig. 3 represents a detail-view (enlarged) of one of the cylinder-gudgeons, showing in section the sprocket wheel mounted thereon.

25 A designates the machine frame; B, the cylinder mounted thereon having end flanges B' and carrying longitudinal bars D and type rods E and lines of type F, all described in my application #325343, of which this is a 30 division.

G designates the table over which the sheets of paper are fed under the cylinder and between it and the platen roller I. This table is hinged at one end at h, and is drawn 35 upward by a spring J after each depression by the paper-feed-roll K. The action of this spring also compensates for the diminution of the pile of paper as each sheet is withdrawn. To control the upward movement 40 of said table, I employ a stop L, which is a nut threaded on a screw-rod M and arranged above a plate N, projecting from said table, said plate being perforated to let it slide up and down on said rod. The latter is operated 45 step by step by a pawl carried by said table and engaging a ratchet wheel O' mounted on a short, horizontal, relatively fixed shaft O² and carrying a bevel wheel P, which meshes with a similar wheel P' on the 50 lower end of the said screw-rod, to turn the same. The said pawl and ratchet are constructed and arranged to feed the said nut or stop upward at each stroke a distance corresponding approximately to the thickness of a 55 sheet of paper; so that each depression of

said table provides for adjusting the surface to be printed on to the position which it should occupy with respect to the printing cylinder for the next impress. The said paper-feed roller is mounted on a bifurcated 60 arm K' of a shaft K², provided with a sprocket wheel or equivalent gear Q connected by an endless driving chain or belt Q' to another sprocket wheel Q² of diameter equal to Q and fastened to one of the gudgeons B² of the cylinder B by a screw q, also by a stud q² of the gudgeon, fitting into a socket q' of the latter sprocket wheel. By removing said screw, the wheel Q² is left free to be removed from the said gudgeon, the 70 said stud being readily pulled out of the socket.

A graduated disk R is fast on shaft K² between the two parallel plates of arm K'; and is engaged peripherally by a clamping 75 screw R' which passes through the bent outer end of said arm to lock the said arm in any desired position of pivotal adjustment. The roller K will always strike the paper opposite the same point on the table G, but 80 it will travel through a greater or less arc of a circle in doing so according to the adjustment of frame K' circumferentially forward or backward by the means aforesaid; and the type cylinder will turn correspondingly 85 more or less during the increased or diminished period of time required by the roller K in reaching the paper, since the disk R and cylinder W are rotated by the same power at the same speed and simultaneously. Of 90 course the paper does not move forward until the feeding roll K reaches it. Hence the above adjustment enables me to determine and vary the point on the paper at which the printing shall begin without ad- 95 justing the type cylinder or moving the platen roller in any way, and as the screw R' may be shifted to any graduation on the disk, this adjustment may be so exact as to insure the beginning of printing precisely at the desired 100 line of the paper and by the chosen line of type on the type cylinder.

The printing ribbon S normally winds from spring roller T to spring roller U, automatically returning to the latter. The platen roller I is journaled in supports I' and held in position by a spring V bearing at V⁴ against the end of a lever I² which is pivoted at its middle on one of the platen roller journals, the said roller being mounted on sup- 110

- porting links I' and the said spring being adjusted by a screw V'. The said ribbon-operating devices and platen-supporting devices are more fully described and claimed 5 in my said application #325343. The cylinder B is driven by gear wheels W and W', the latter being mounted on a shaft W² and locked at will by a stud W³ as described and claimed in said application.
- 10 X designates a guide frame bearing on the pile of paper sheets, as shown in my patent #825186, and movable with said sheets up and down on studs X' of said feed table. The latter bears also guide plate X² for the 15 sides of the paper. Said table rests on a box Y which supports some minor parts of the machine and may hold tools. The herein-described nut L may be locked by a chain and pin L'.
- 20 The operation of this invention has been hereinbefore sufficiently explained.
- Having thus described my invention, what I claim as new and desire to secure by Letters Patent is:
- 25 1. In combination with a printing cylinder and a depressible paper-feeding table, paper-feeding mechanism, comprising an arm carrying a device arranged for contact with the paper and simultaneous depression of 30 the said table, means for automatically raising the table after such depression sufficiently to compensate for the thickness of the sheet of paper thus removed and means for varying the movement of said arm and thereby 35 regulating the interval before the said device acts on the paper to feed the same as set forth.
2. In combination with a printing cylinder and a depressible paper-feeding table, a 40 paper-feeding roller, an arm on which said roller is mounted, means for causing said roller to descend on the paper and table, moving forward the former and depressing the latter, a spring for raising the said table 45 automatically, means for regulating the action of the said spring, in order that it may compensate for the thickness of each layer of paper removed, and means for adjusting the travel of said arm and roller thereby regulating the interval before the said roller feeds 50 the paper substantially as set forth.
3. In combination with a printing couple, a depressible paper-supporting table means for elevating said table operated by such depression, a rotary shaft, an arm carried by 55 said shaft and adjustable circumferentially thereon to vary the interval before the feeding action and an inflexible device carried by said arm and arranged to feed a sheet of paper and simultaneously depress said table substantially as set forth.
4. In combination with a printing couple, a depressible paper-supporting table, paper feeding mechanism comprising an arm carrying a device arranged for contact with the pa- 60

per and simultaneous depression of the said table, positively acting means for automatically raising the table after such depression sufficiently to compensate for the thickness of the sheet of paper thus removed and means for varying the movement of said arm and thereby regulating the interval before the said device acts on the paper to feed the same as set forth. 70

5. In combination with a rotary printing cylinder, a depressible paper supporting table, means positively operated by the machine for elevating said table, a rotary shaft, an arm carried by said shaft and adjustable circumferentially thereupon to vary the interval before the feeding action and a roller carried by said arm and arranged to feed a sheet of paper and simultaneously depress said table substantially as set forth. 75

6. In combination with a printing couple, 80 a depressible paper supporting table, a rotary shaft, an arm carried by said shaft and adjustable circumferentially thereon to vary the interval before the feeding action, positively acting mechanism for elevating the 85 said table and an inflexible device carried by said arm and arranged to feed a sheet of paper and simultaneously depress said table substantially as set forth.

7. In combination with a printing couple, 90 a depressible paper supporting table, a rotary shaft, an arm carried by said shaft and adjustable circumferentially thereon to vary the interval before the feeding action, means operated by the depression of said table for 95 automatically elevating the said table and an inflexible device carried by said arm and arranged to feed a sheet of paper and simultaneously depress said table substantially as set forth. 100

8. In combination with a printing couple, 105 a depressible paper-supporting table, a rotary shaft, an arm carried by said shaft and adjustable circumferentially thereon to vary the interval before the feeding action, positively operating means for automatically elevating the said table and an inflexible device carried by said arm and arranged to feed a sheet of paper and simultaneously de- 110 press said table substantially as set forth. 115

9. In combination with a printing couple, a depressible paper-supporting table, a rotary shaft, an arm carried by said shaft and adjustable circumferentially thereon to vary the interval before the feeding action, means 120 operated by the depression of said table for automatically elevating the said table, and a device carried by the said arm and arranged to feed a sheet of paper and simultaneously depress said table substantially as set forth. 125

10. In combination with a printing couple, a depressible paper-supporting table, means, operated by the depression of the table, for elevating the latter, a shaft turning on its axis, and a device moving with said shaft to 130

- feed a sheet of paper and simultaneously depress the said table, said device being adjustable on said shaft to vary the interval before the feeding action substantially as set forth.
- 5 11. In combination with a printing couple, a depressible paper-supporting table, means, operated by the depression of the table, for elevating the latter, a shaft turning on its axis, and a device moving with said shaft to feed a sheet of paper, said device being adjustable on said shaft to vary the interval before the feeding action substantially as set forth.
- 10 12. In combination with a printing cylinder a shaft geared to and rotating with said cylinder, an arm carried by said shaft, a paper-feeding roller carried by said arm and means for adjusting the said arm circumferentially on said shaft to vary the interval before the said feeding roller acts on the paper, the said printing cylinder being unaffected in position by the above adjustment of the feeding roller substantially as set forth.
- 15 13. In combination with a printing cylinder, a paper-feeding device, an arm carrying the same, a shaft on which said arm is mounted, a graduated disk fast on the said shaft and means for clamping the said arm to said
- disk in any one of several different circumferential positions of said arm to regulate the interval before said device acts on the paper and mechanism for driving the said cylinder and shaft simultaneously, the said printing cylinder being unaffected in position by the above adjustment of the feeding roller substantially as set forth.
- 20 14. In combination with printing mechanism and paper-feeding mechanism, a table for supporting the paper thus fed, means for automatically lifting the said table to compensate for the reduction of the pile of paper, an adjustable screw-threaded stop engaging an attachment of said table to control its upward movement, a screw-threaded rod engaging said stop and a pawl and ratchet and intermediate device whereby the action of said paper-feeding device feeds up the said stop approximately the thickness of a sheet of paper substantially as set forth.
- 25 In testimony whereof, I have signed my name to this specification in the presence of two subscribing witnesses.
